US0D1051316S

(12) **United States Design Patent** (10) **Patent No.:** **US D1,051,316 S**
(45) **Date of Patent:** **** Nov. 12, 2024**

(54) **HEATER**

(71) Applicant: **Shenzhen Maijindian Technology Co., Ltd.**, Shenzhen (CN)

(72) Inventor: **Qian Li**, Shenzhen (CN)

(73) Assignee: **Shenzhen Maijindian Technology Co., Ltd.**, Shenzhen (CN)

(**) Term: **15 Years**

(21) Appl. No.: **29/956,941**

(22) Filed: **Aug. 9, 2024**

(30) **Foreign Application Priority Data**

Jul. 30, 2024 (CN) 202430477777.1

(51) **LOC (14) Cl.** **23-03**

(52) **U.S. Cl.**
USPC **D23/336**

(58) **Field of Classification Search**

USPC D23/322, 323, 332, 333, 334, 335, 336,

CLAIM

The ornamental design for a heater, as shown and described.

DESCRIPTION

FIG. 1 is a front, right and top perspective view of a heater, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the heater that form no part of the claimed design.

1 Claim, 8 Drawing Sheets
